STAPLE DISPENSER

Julius Rudberg and Theodore E. Keller, Los Angeles, Calif.; said Keller assignor to said Rudberg

Application October 18, 1948, Serial No. 55,218

6 Claims. (Cl. 1—49.7)

1

The invention relates to a staple dispenser and, more particularly to a dispenser for staples commonly known as hog rings. Such staples are substantially U-shaped with converging legs or sides. The staple is brought somewhat into the shape of a ring by grasping the staple with a pair of pliers having jaws with offset grooves therein to bend one leg of the staple across the other when the pliers are operated.

While such staples are employed to form a ring in a hog, this invention is more concerned with another well known use, namely, to anchor a seat cover onto the metal frame work of an automobile seat. The disadvantage in this use is that it takes a certain amount of time to place the staple in proper relation in the jaws of the pliers in the course of forming the ring. According to one proposal, a hopper for the staples has been mounted on the pliers, but this solution is not satisfactory as the hopper is a rather large protuberance which interferes with the free use of the pliers.

An object of the present invention is to overcome the above defects and to provide a dispenser which will store a stack of staples so that they are accessible one at a time for grasping by the pliers.

According to the invention the stack of staples is slidably supported on a post having sections, one of which is rigid to prevent lateral withdrawal of the staples while the other section is collapsible to permit lateral withdrawal of a staple. The invention also provides means for feeding the stack of staples from the rigid post section to the collapsible section, as well as means for guiding the jaws of the pliers into operative relation with a staple on the collapsible section.

For further details of the invention, reference may be made to the drawings wherein

Fig. 1 is a side view in elevation of a staple dispenser according to the present invention.

Fig. 2 is a front view in elevation.

Fig. 3 is a top plan view.

Fig. 4 is a sectional view on line 4—4 of Fig. 2 looking in the direction of the arrows.

Fig. 5 is an enlarged sectional view on line 5—5 of Fig. 2 looking in the direction of the arrows, with parts broken away.

Fig. 6 is a sectional view on line 6—6 of Fig. 5 looking in the direction of the arrows, with pliers shown in broken lines.

Fig. 7 is an exploded view showing in perspective the post and pivoted shelf members employed in the dispenser shown in the other figures.

2

Referring in detail to the drawings, the dispenser 1 is arranged to dispense a so-called hog ring, in the form of a staple having legs which converge towards the ends of the legs as illustrated at 2 in Fig. 6. A stack of staples like 2 is indicated in Fig. 1 at 3 on an upright post 4. A circular array of such parallel posts, here indicated as five in number and indicated at 4, 5, 6, 7 and 8 in Fig. 3, are arranged on a turntable 9, see Fig. 5. The turntable 9 has a hollow cylindrical rim 10 and each post like 4 is secured thereto by a screw like 11 which passes through the rim 10 into the base of the post. The turntable 9 (Fig. 5) is rotatably supported on the cylindrical surface 12 of a screw 13 which has a flange 26 to rotatably hold the turntable 9 in position on a stop plate 14. The screw 13 has threaded engagement as indicated at 15 with the top of the tilt head 16. The stop plate 14 rests on the elevated rear top surface 17 of the tilt head 16 and is secured thereto by screws like 18.

Each post like 4 has a surface contour the same shape as the inside of the staple, namely, with sides which converge, so that the staples like 2 cannot be withdrawn horizontally from the post like 4, the distance between the inner ends 20, 21, see Fig. 7, of the staple being less than all portions of the staple in front of the ends of such legs. Each post like 4 slidably supports its stack 3 of staples, and a new stack can be fitted endwise on the post.

Each stack of staples has on top thereof a sliding weight like 22, see Fig. 5, each such weight having an aperture of the same contour as the post like 4, and each such weight at the front and sides of such post having a downwardly extending sleeve extension 23, see Fig. 5, to force the staples into the tilt head 16.

The stop plate 14 as shown in Fig. 4 serves as a mask and has a somewhat U-shaped slot 25 of the same shape as, and slightly larger than, the staple, so that when a particular post such as 4 is in alignment with the slot 25, the staples will pass through such slot and on to a lower post 30, see Fig. 7. The post 30 is stationary and it has a somewhat U-shaped contour 31 the same as that of the inside of the staple like 2 and the same as that of each of the posts like 4. The post 30 has a base portion 32 which fits in a recess 33 in the top of the tilt head 16. The base 32 is held in the recess 33 by a screw 34 which engages a threaded aperture 35 in the base 32.

The stop plate 14 overlies and rests on the top 55 of the post 30 as indicated at 36 in Fig. 5, with

the contour 31 of the staple guiding portion in alignment with the slot 25.

Each post like 4 is brought into alignment with the fixed post 30 as follows. The post 30 has a spring barrel 40 for a compression spring 41 which urges upwardly a ball detent 42. The stop plate 14 has a restricted aperture 43 smaller in diameter than the ball so that the stop plate 14 serves as a retainer for ball 42. Ball 42 projects above the top of plate 14 and engages a recess like 45 in the bottom of each post like 4. When the ball 42 is in a recess like 45, the post like 4 is in alignment with the slot 25 and with the fixed post 30.

The staples like 2 slide down the post like 4 and the post 30, under action of the weight 22. Removal of the bottom staple 50 of a stack is made possible as follows. The front upper portion 51 of the recess 33 is enlarged opposite the staples so that they can slide downwardly into the head 16, to a point opposite a lateral opening 52 where the stack is supported by the shelf portions 53, 54 on a collapsible post 55. The shelf 53, 54 is elevated above the bottom 71 of recess 33 to receive the pliers 75. The post 55 comprises post portions 56 and 57 each hinged to the bottom of post 30 by a screw like 58, see Fig. 5. The post portions 56 and 57 are urged apart by a compression spring 59, see Fig. 6, having ends arranged in spring barrels 60 and 61 in the members 56 and 57, respectively. The separation of the post portions 56 and 57 can be adjusted by two adjusting screws 62 and 63 arranged in the head 16. The screws 62 and 63 are adjusted so that the staples like 2 will slide down post 30 onto, and be supported by, the shelf portions 53 and 54, with the staple fitting the L-shaped surface 64 on the member 56 and the L-shaped surface 65 on the other member 57. The L portions 64 and 65 form a continuation of the corresponding side and front portions of the post 31, with a gap 66 opposite the middle of the bight of the staple between the members 56 and 57 so that they can be compressed against the action of spring 59 to a width less than the minimum width between the staple legs to release the bottom staple 50 of a stack. The height of the members 56 and 57 is preferably slightly greater than that of the lowermost staple 50, as shown in Fig. 5 so as to facilitate removal of the bottom staple.

The lateral opening 52 is flared out as indicated at 70 in Fig. 6, and the vertical opening 51 is wide enough at opposite sides of the collapsible post 55 to permit entry of the jaws 71, 72 of the pliers 75.

The jaws 71, 72 are shown in section in Fig. 2 and each has a shallow groove 73, 74, respectively, as well known, to grasp the opposite sides of the staple, the jaws 71, 72 being offset so that the legs of the staple will cross when the jaws of the pliers are squeezed together.

A bottom staple 50 lies in a plane at right angles to the post 30, and to compensate for the fact that jaws 71, 72 and their grooves 73, 74 are offset, the jaw openings 70 and 52 are tilted slightly as shown in Fig. 2 so that when the jaws 71, 72 are inserted, the grooves 73, 74 are opposite the sides of the staples 50 in position to grasp the staple 50.

When the bottom staple 50 is grasped by the pliers 75 by pulling on the pliers, the bottom staple 50 is pulled off from the collapsible post 55, against the action of spring 59. The next upper staple 76 drops into position on the shelf

members 53, 54 ready to be again grasped and removed by the pliers 75. After a particular stack of staples has been removed by the pliers, the sliding weight like 22 is lifted and the turn table 9 rotated to bring the next post like 5-3 with its stack of staples thereon, into position as shown in Fig. 5.

If desired, the tilt head 16 can be tilted more or less to suit the convenience of the operator and for this purpose the tilt head has a clamp screw 80 to releasably clamp the axle 81 on the base 82. The base 82 has suitable apertures like 83 for bolts to hold the base to a suitable support.

If desired, one may dispense with the plurality of posts above indicated as well as stop plate 14, and use a single post instead, such post being the same as post 30 in Fig. 7 except that it would be somewhat longer like post 4 in order to hold a stack of staples.

Various other modifications may be made in the invention without departing from the spirit of the following claims.

We claim:

1. A dispenser for staples each substantially U-shaped and having converging sides, said dispenser comprising a post adapted to support a stack of such staples for longitudinal sliding movement thereon, said post having a contour substantially the same as the inside of such staple and having a front portion wider than the minimum width of the legs of the staple to prevent lateral withdrawal of the staples from said post, said post having a conjoining collapsible post, said collapsible post having a shelf to support the end staple of a stack, said collapsible post having a height at least as great as one staple and less than two staples, said collapsible post having a contour fitting the inside of the staple at certain times and being collapsible to permit lateral withdrawal of a staple.

2. A dispenser according to claim 1 wherein said collapsible post comprises an opposite pair of post sections, a hinge connection between each of said sections and the bottom of said first post, spring means urging said sections apart and adjusting screws for opposing the action of said spring.

3. A dispenser comprising a head having a vertical recess and a lateral opening which opens into the lower portion of said vertical recess, a fixed post in said vertical recess, a collapsible post at the bottom of said first post and arranged opposite said lateral opening, said posts comprising means for longitudinally guiding a stack of staples each having converging legs, said first post having a front portion of a width greater than the minimum widths between the legs of the staple to prevent lateral withdrawal of the staple, said collapsible post being collapsible to permit lateral withdrawal of the staple thereon, said lateral opening providing access for a tool to grasp a staple on said collapsible post.

4. A dispenser according to claim 3 comprising a movable member having thereon a plurality of parallel posts each having a contour substantially the same as that of said first post, means movably supporting said member on said head and means for locking any one of the posts on said member in alignment with said first post.

5. A dispenser comprising a head having a fixed post terminating at its lower end in a collapsible post, a stop plate at the top of said fixed post, a rotary magazine having a plurality of parallel posts adapted to be brought into

alignment, one at a time, with said fixed post, said fixed post, said collapsible post and said magazine posts all having a contour substantially fitting the inside of a substantially U-shaped staple having converging legs, a slot in said stop plate substantially the shape of the staple and in alignment with said fixed post for passing a staple from one of said magazine posts to said fixed post, said collapsible post being collapsible to the minimum width of the staple to permit lateral withdrawal of the staple thereon, means urging a stack of staples lengthwise of one of said magazine posts through said slot onto said fixed post and onto said collapsible post, and means for guiding a tool into engagement with a staple on said collapsible post.

6. A dispenser for staples each substantially U-shaped and having converging sides, said dispenser comprising a post having conjoining longitudinal sections adapted to support a stack of

5
10

such staples for longitudinal sliding movement thereon, one of said sections being rigid and having converging sides on which the staples slidably fit to prevent lateral withdrawal of the staples, the other of said sections having a height at least as great as one staple and less than two staples and being collapsible for lateral withdrawal of one staple, and means for feeding a stack of staples from said rigid section to said collapsible section.
